UNITED STATES PATENT OFFICE

THEODORE H. GOODNOW AND KENNETH J. TOBIN, OF CHICAGO, ILLINOIS, ASSIGNORS
TO CAMEL COMPANY, A CORPORATION OF ILLINOIS

CAR DOOR

Application filed October 1, 1928. Serial No. 309,411.

This invention relates to a sliding door for house cars, and concerns itself with a structure which will eliminate the usual coopering required in connection with the loading of such cars. To this end, there is provided a side door with a wood lining, so that commodities such as bags of flour, sugar, cement and the like may be loaded against the door without any danger of their coming in contact with metal parts, and means are provided for bracing the door against outward thrust.

The invention comprises the novel structure and combination of parts hereinafter described and more particularly pointed out and defined in the appended claims.

In the accompanying drawings which illustrate a preferred embodiment of this invention and in which similar reference numerals refer to similar features in the different views:

Figure 1 is a fragmentary side elevational view of a car embodying a door involving this invention.

Figure 2 is an enlarged fragmentary sectional view taken upon the line II—II of Figure 1.

Figure 3 is an enlarged sectional view taken upon the line III—III of Figure 1.

Figure 4 is a sectional view taken upon the line IV—IV of Figure 1.

Figure 5 is a fragmentary part elevational and part detail view of a modified form.

As illustrative of this invention, there is shown a sliding car door 1 mounted upon a track 2 by means of rollers 3. It is, however, immaterial whether the door is supported upon a lower or upper track. This door consists of an outer sheet metal panel 4 which, in the present instance, is shown as corrugated, and an inner lining of wood 5.

A plurality of vertical thrust resisting members 6 somewhat in the form of channel bars are secured to the sheet metal panel of the door and extend above and below the door. The upper and lower terminals of these members are inwardly offset, as indicated at 6a. Upon the upper side plate 7 of the car there are a plurality of keepers 8 which are spaced apart the same distance as

the members 6, and upon the sill 8 of the car there are a plurality of similarly spaced keepers 9. These keepers have sloping or cam surfaces 8a and 9a, which in the present instance are shown as arcuate, for drawing the door inwardly. The upper edge of the door is slidably confined in a suitable guide-way 10 formed by attaching an angle bar 11 to the side plate 7 which is shown in the form of a Z bar.

In the present instance, the door 1 is illustrated at the corner of the car and cooperating with a swingable rear door 12, which is locked in position by a swingable bar 13 engaging under suitable keepers 14 and 15 above and below such door. The rear door 12 is provided with a groove or lodgement 16 for receiving the front edge of the sliding door 1, for weatherproofing purposes and for preventing outward thrust. It will, however, be appreciated that the invention is not limited to corner doors.

The arrangement of the thrust resisting bars 6 and keepers 8 and 9 is such that the terminals of the bars 6 are under the keepers when the door 1 is closed and accordingly resist any outward thrust of such doors when material is loaded against the door, and, as the door has a wood lining, the material will not come in contact with the metal, consequently, there is no need to cooper a car when the doors are constructed according to this invention.

In the modified form shown in Figure 5, the thrust resisting bars 6 are shown with hook shaped ends 17, which engage hook shaped guiding keepers 18. The ends of the hooks on the guide 18 may be bevelled so as to slope just as the keepers 9, as indicated at 19, consequently the thrust bars 6 may also serve as tieing members with respect to parts of the car.

Apparently as the thrust resisting member 6 upon the right hand side of the door must pass under the right hand keepers 8—9, when the door is opened, these keepers slope in both directions, or in other words they have an inner arcuate surface.

We are aware that many changes may be made and numerous details of construction

may be varied through a wide range without departing from the principles of this invention, and we, therefore, do not purpose limiting the patent granted hereon otherwise than necessitated by the prior art.

5. We claim as our invention:

1. The combination with a door having vertical thrust-resisting members spaced a material distance from the vertical margins of the door, and keepers above and below said door under which said members pass when said door is closed for resisting the outward thrust thereof.

10. 2. In a house car having a doorway, a sliding door mounted in said doorway, vertical thrust resisting members upon said door, and keepers having sloping surfaces adjacent the margins of said doorway adapted for receiving the ends of said members when said door is closed.

15. 3. In a house car having a doorway, a sliding door mounted in said doorway, said door comprising an outer metal panel and an inner wooden lining, vertical thrust resisting members secured to said metal panel, and keepers adjacent the upper and lower margins of said door under which the ends of said members pass when the door is closed for resisting the outward thrust thereof.

20. 4. In a house car having a doorway, a sliding door mounted in said doorway, a plurality of bars secured to said door and extending above and below the ends thereof, and keepers with sloping surfaces adjacent the upper and lower margins of said doorway under which the ends of said bars are adapted to extend when said door is closed for resisting the outward thrust thereof.

25. 5. In a house car having a doorway, a door for closing said doorway, a thrust resisting member upon said door and spaced substantially from the margins thereof and keepers adjacent the margins of said doorway under which said thrust resisting members are adapted to pass when the door is closed for resisting the outward thrust thereof.

30. 6. In a house car having a doorway, a door for closing said doorway, thrust resisting members upon said door and having hook shaped ends, and keepers upon the car under which said hook shaped ends engage.

35. 7. As an article of manufacture, a car door consisting of an outer sheet metal panel and a wooden lining, and thrust resisting members secured to said metal panel.

40. 8. As an article of manufacture, a car door consisting of an outer sheet metal panel and an inner wooden lining, and vertical thrust resisting members extending co-extensive with the door secured to the metal panel.

45. In testimony whereof, we have hereunto subscribed our names at Chicago, Cook County, Illinois.

THEODORE H. GOODNOW.

65. KENNETH J. TOBIN.
